GOLF PUTTER HEAD

Raymon W. Cook, San Antonio, Tex., assignor to Ray Cook Golf Putters, Inc., San Antonio, Tex.

Continuation of abandoned design applications Ser. No. 293,531, Sept. 29, 1972, and Ser. No. 343,389, Mar. 21, 1973. This application June 14, 1974, Ser. No. 479,459

Term of patent 14 years

Int. Cl. D21—02

U.S. Cl. D34—5 GH

FIG. 1 is a front elevational view of a golf putter head showing my new design.

FIG. 2 is a front end view of FIG. 1.

FIG. 3 is a top plan view of FIG. 1.

FIG. 4 is a rear elevational view of FIG. 1.

FIG. 5 is a vertical sectional view, taken on the line 5—5 of FIG. 4, looking in the direction of the arrows.

FIG. 6 is a bottom plan view of FIG. 1.

FIG. 7 is a front elevational view of another embodiment of my invention.

FIG. 8 is a front end view of FIG. 7.

FIG. 9 is a top plan view of FIG. 7.

FIG. 10 is a rear elevational view of FIG. 7.

FIG. 11 is a vertical sectional view, taken on the line 11—11 of FIG. 10, looking in the direction of the arrows.

FIG. 12 is a bottom plan view of FIG. 7.

This is a continuation of design patent applications D. 293,531, filed Sept. 29, 1972, and D. 343,389, filed Mar. 21, 1973, both now abandoned.

I claim:

The ornamental design for a golf putter head, as shown and described.
